US00D877506S

(12) **United States Design Patent** (10) **Patent No.:** **US D877,506 S**
(45) **Date of Patent:** **** Mar. 10, 2020**

(54) **LUGGAGE**

- (71) Applicant: **JRSK, Inc.**, New York, NY (US)
(72) Inventors: **Stephanie Korey**, New York, NY (US);
Jennifer Rubio, New York, NY (US);
Bret Recor, San Francisco, CA (US);
Seth Murray, San Francisco, CA (US);
Charles Weber, San Francisco, CA (US);
Ahyoung Park, San Francisco, CA (US)
(73) Assignee: **JRSK, Inc.**, New York, NY (US)
(**) Term: **15 Years**
(21) Appl. No.: **29/609,834**
(22) Filed: **Jul. 6, 2017**

Related U.S. Application Data

- (63) Continuation of application No. 14/935,335, filed on Nov. 6, 2015, now Pat. No. 10,219,599.
(51) **LOC (12) Cl.** **03-01**

CLAIM

The ornamental design for a luggage, as shown and described.

DESCRIPTION

FIG. 1 is a rear perspective view of a piece of luggage showing our new, original and ornamental design embodied therein, in accordance with the present invention; FIG. 2 is a front perspective view of the piece of luggage of FIG. 1; FIG. 3 is an elevated front view of the piece of luggage of FIG. 1; FIG. 4 is an elevated rear perspective view of the piece of luggage of FIG. 1; and, FIG. 5 is a bottom view of the piece of luggage of FIG. 1. Any dash-dash broken lines in the drawings, including any dash-dash broken line over a claimed surface, represent unclaimed portions of the piece of luggage and form no part of the claimed design.

1 Claim, 5 Drawing Sheets
